United States Patent Office

Des. 180,259
Patented May 7, 1957

180,259

BOOT OR SIMILAR ARTICLE

Harold Zisla, South Bend, Ind., assignor to United States Rubber Company, New York, N. Y., a corporation of New Jersey

Application February 3, 1956, Serial No. 40,024

Term of patent 3½ years

(Cl. D7—7)

Fig. 1

Fig. 3

Fig. 2

Fig. 4

Fig. 1 is a side elevational view of a boot showing my new design;

Fig. 2 is the opposite side view of the boot from that shown in Fig. 1;

Fig. 3 is a front view of the boot; and

Fig. 4 is a rear view of the boot.

I claim:

The ornamental design for a boot or similar article, as shown.
